UNITED STATES PATENT OFFICE.

EDWIN MAHLON MASON, OF CRAWFORDSVILLE, INDIANA, ASSIGNOR TO THE SUPREME TRIBE OF BEN HUR, OF CRAWFORDSVILLE, INDIANA.

DESIGN FOR A CERTIFICATE.

52,850.

Specification for Design.

Patented Jan. 7, 1919.

Application filed August 8, 1918. Serial No. 249,014. Term of patent 7 years.

To all whom it may concern:

Be it known that I, EDWIN M. MASON, a citizen of the United States, residing at Crawfordsville, in the county of Montgomery and State of Indiana, have invented a new, original, and ornamental Design for a Certificate, of which the following is a specification, reference being had to the accompanying drawing, forming part thereof.

The figure is a face view of a certificate, showing my new design.

I claim:—

The ornamental design for a certificate, as shown.

EDWIN MAHLON MASON.

Copies of this patent may be obtained for five cents each, by addressing the "Commissioner of Patents, Washington, D. C."
